ELECTRICAL CONDUCTOR TERMINAL

Luis de Urzaiz, New York, N. Y.

Application February 20, 1940, Serial No. 319,973

2 Claims. (Cl. 173—259)

This invention relates to new and useful improvements in terminals for electrical conductors, and more particularly to terminals for connecting conductors to electric batteries of the storage type.

One object of the invention is to provide an improved terminal of the type mentioned which may be quickly and easily applied to and detached from the post of a battery without the use of a tool.

A further object is to provide a terminal which cannot be detached from the battery post by accident.

A still further object is to provide a terminal of the general type disclosed in United States Patent Number 2,128,888, dated August 30, 1938, but wherein the spring clamp may be readily placed in surrounding relation to the jaws of the terminal, from the upper face thereof.

Other objects and advantages will be apparent from the following description when taken in connection with the accompanying drawing, in which

Fig. 1 is a plan view of the connector,

Fig. 2 is a side elevation of the same,

Fig. 3 is a section on the line 3—3 of Fig. 1,

Fig. 4 is an end view of the connector,

Fig. 5 is a section on the line 5—5 of Fig. 1,

Fig. 6 is a section on the line 6—6 of Fig. 1, but showing the connector in position on the battery post,

Fig. 7 is a detail perspective view of the connector detached from the post,

Fig. 8 is a perspective view illustrating a spring clamp for holding the connector in attached position, and

Fig. 9 is a perspective view of the connector showing the manner in which the spring clamp is applied thereto.

Referring to the drawing, 10 designates a tubular member within which an end of the conductor 11 is supported. Formed on and extending from one side of the member 10 is a lug 12, the outer end of which is formed integral with an arcuate clamping jaw 13. A side portion of the lug 12 is reduced in thickness as at 14. To this reduced portion 14 is pivotally connected an arcuate clamping jaw 15 similar to the jaw 13. The inner end of the jaw 15 is bifurcated, resulting in furcations which straddle the reduced portion 14. A pin 16 passes through the furcations of the jaw 15 and through the reduced portion 14 of the lug 12, whereby the said jaw 15 is pivotally connected to said reduced portion and may be swung toward or away from the jaw 13.

As shown in Figs. 4 and 7, the outer peripheral

face of the jaw 13 is provided with a groove 17 which extends entirely therearound, while the corresponding face of the jaw 15 is smooth. As shown in Fig. 5, the inner faces of the jaws 13 and 15 are inclined inwardly and downwardly so that when they are in closed position, as shown in Fig. 1, the openings between the jaws is of the shape of a truncated cone with its smaller end downward. This construction is provided in order that the inner faces of the jaws will snugly fit the downwardly tapered battery post 18, as shown in Fig. 6. Because of the shape of this post and the corresponding shape of the inner faces of the jaws, the terminal cannot move upwardly from the post after its jaws have been clamped thereon in a manner now to be described.

In Fig. 8 there is illustrated a spring clamp 19 which is employed for drawing the jaws 13 and 15 together so as to hold the same tightly to the post 18. This clamping spring consists of a flat spring band in the form of an open loop having the free end of its side portion 20 curved outwardly to a slight degree as at 21 and having the free end of its other side portion 22 bent sharply to extend outward and then given a half turn to form a thumbpiece 23.

When applying this improved terminal to the battery post, the arcuate jaws 13 and 15 are placed in surrounding relation to the battery post 18 so as to conform with its taper. The side portion 20 of the spring clamp 19 is then positioned to rest within the groove 17 of the jaw 13, as shown in Fig. 9. By placing the thumb upon the thumbpiece 23, the side portion 22 of the spring clamp is then forced downwardly over the jaw 15 and into engagement with its outer or vertical face. Because of the binding action of the spring clamp 19, the jaws of the terminal will be held in tight engagement with the post 18 and cannot be removed therefrom without first removing the spring clamp by an upward pressure on its thumbpiece 23. After the removal of the spring clamp, the jaw 15 may be swung upon its pivot 16 and the terminal removed from the battery post.

What is claimed, is:

- Means for connecting an electrical conductor to a battery post, including a conductor end support, an arcuate clamping jaw formed integral with said support, an arcuate clamping jaw pivotally connected to said support, the outer peripheral face of one of said jaws being grooved and the corresponding face of the other of said jaws being smooth, and a spring clamp surrounding said jaws for drawing the same together, said

clamp being in the form of an open loop and having a side portion disposed in said groove, and a side portion disposed against said smooth face of the other jaw, the last-named side portion having a thumbpiece whereby the clamp may be moved longitudinally of the battery post.

2. Means for connecting an electrical conductor to a battery post, including a conductor end support, an arcuate clamping jaw formed integral with said support, an arcuate clamping jaw 10 pivotally connected to said support, the outer peripheral face of one of said jaws being grooved

5 and the corresponding face of the other of said jaws being smooth, and a spring clamp surrounding said jaws for drawing the same together, said clamp being in the form of an open loop and having a side portion disposed in said groove and a side portion disposed against said smooth face of the other jaw and the last-named side portion having an end portion bent outwardly and twisted to form a thumbpiece in a plane parallel to the upper faces of the jaws.

LUIS DE URZAIZ.
